United States Patent Office

Des. 177,889
Patented May 29, 1956

177,889

TORQUE GAUGE

Robert A. Waters, Weston, Mass.

Application November 16, 1954, Serial No. 33,117

Term of patent 14 years

(Cl. D52—1)

Fig. 2.

Fig. 1.

Fig. 3.

Figure 1 is a side elevational view of a torque gauge, showing my new design;

Figure 2 is a face view thereof; and

Figure 3 is an end view opposite to the face of the gauge.

I claim:

The ornamental design for a torque gauge, as shown.
